UNITED STATES PATENT OFFICE

WILLIAM H. YARBOROUGH, OF SHERMAN, TEXAS.

IMPROVEMENT IN DOUBLE-BITTED DRILLS.

Specification forming part of Letters Patent No. 178,220, dated May 30, 1876; application filed October 20, 1875.

To all whom it may concern:

Be it known that I, WILLIAM H. YARBOROUGH, of Sherman, Grayson county, and State of Texas, have invented a new and useful Improvement in Double-Bitted Drills, which improvement is fully set forth in the following specification, reference being had to the accompanying drawings.

The object of my invention is to provide an easy mode of straightening wells while drilling them through rock or earth, and also for enlarging the same into a cistern when it is desired to keep on hand a large supply of water. This I am enabled to accomplish with the double-bitted drill, hereinafter more fully described, consisting of a vertical stem, *a*, and two curved cutting-bits or chisels, *b b*, constructed as shown in the vertical side view, Figure 1, and front view, Fig. 2, of the accompanying drawing.

It has not been deemed necessary to show the drill attached to any particular well-boring machine, as it may be operated by any well-known apparatus for that purpose.

The top of the stem *a* is provided with an eye, through a hole in which passes a rope, that is prevented from drawing through by a knot upon the under side. This rope should extend upward over a pulley and connect with any suitable mechanism that will raise the drill and let it fall. The bottom of the stem is forked, to receive the bits or chisels

b b, each of which is provided with a cutting-edge at the bottom and up the outside, and they are secured to the stem by a bolt, *c*, which passes loosely through them near the top of each. These bits curve outward toward the bottom, and when the drill is suspended their points stand a slight distance apart.

The manner of operating this drill is substantially the same as other rock-drills. It is raised by machinery and let fall, when the curved points of the bits strike upon the rock, forcing them apart in opposite directions, and also forcing their sharp edges against the sides of the well, cutting it away in a circular form, by its weight and momentum. A sufficient quantity being chipped off and mixed with the water, that is always used when drilling in rock, the drill is drawn out and a sand-bucket is let down and the drillings taken out, when the operation is repeated.

Having thus described my invention, what I claim as new, and desire to secure by Letters Patent, is—

A double-bitted drill, consisting of a stem, *a*, and two curved cutters, *b b*, pivoted as shown, and operated as and for the purpose herein set forth.

WILLIAM H. YARBOROUGH.
